Primary Examiner — Jasmine Mlinarcik(74) *Attorney, Agent, or Firm* — Stephen J. Weyer, Esq.; Stites & Harbison, PLLC(57) **CLAIM**

The ornamental design for a head sheet, as shown and described.

DESCRIPTION

FIG. 1 is a perspective view taken from the front, left side, and top side of the head sheet showing my design.

FIG. 2 is a perspective view taken from the rear, right side, and bottom side thereof.

FIG. 3 is a front view thereof.

FIG. 4 is a rear view thereof.

FIG. 5 is a left side elevation view of thereof, the right side being a mirror image thereof; and,

FIG. 6 is a top plan view thereof.

The dashed lines along the surfaces of the head sheet depict an embroidered pattern that forms a part of the claimed design.

1 Claim, 6 Drawing Sheets(56)
